UNITED STATES PATENT OFFICE

2,365,512

MULTIVIBRATOR

Everhard H. B. Bartelink, West Milton, N. Y., assignor to General Electric Company, a corporation of New York

Application March 24, 1943, Serial No. 480,337

3 Claims. (Cl. 250—36)

My invention relates to multivibrators and particularly to synchronizing means therefor. My present application is a continuation in part of my application Serial No. 342,321, filed June 25, 1940, and which is assigned to the assignee of my present application.

My present invention has for one of its objects to provide improved synchronizing means for such multivibrators.

Another object of my invention is to provide means to reduce certain undesired capacity effects in the operation of synchronizing means for multivibrators.

A further object of my invention is to provide means to neutralize the effect of such undesired capacity as may exist between the anode of one of the discharge devices of the multivibrator and the anode of a device employed for synchronizing the multivibrator the anode of which device varies in potential oppositely to that of the anode of said one device.

The novel features which I believe to be characteristic of my invention are set forth with particularity in the appended claims. My invention itself, however, both as to its organization and method of operation, together with further objects and advantages thereof, may best be understood by reference to the following description taken in connection with the accompanying drawing in which the single figure represents an embodiment of my invention.

Referring to the drawing, I have indicated therein a pair of electron discharge devices 1 and 2. Device 1 has an anode 3, a control electrode 4 and a cathode 5. Device 2 has an anode 6, a control electrode 7 and a cathode 8. The anodes 3 and 6 are connected through individual resistances 9 and 10 and a common resistance 11 to the positive terminal of a source of operating potential 12. The cathodes 5 and 8 are connected through individual resistances 13 and 14 to the negative terminal of the source of potential 12. The control electrode of each device is coupled to the anode of the opposite device through respective condensers 15 and 16, and the two control electrodes are connected together through a series of resistors 17, 18 and 19, a variable tap on the intermediate resistor 18 being connected to ground with respect to alternating current by means of a large capacitor 20 and it is connected for direct current through a resistance 21 to a variable tap 22 on a bleeder resistance 23 across the source of potential 12.

The circuit arrangement as thus described comprises the usual multivibrator in which the two

control electrodes are biased positively with respect to the cathodes of the two devices by a variable amount dependent upon the position of tap 22 on resistance 23.

5 When a pulse of current flows in either device, the anode potential on the respective device drops by reason of the potential in the respective resistance 9 or 10 and this drop in potential is transmitted to the control electrode of the opposite device through the respective capacitor 15 or 16, this potential being sufficient to interrupt current in the opposite device. This interruption in current causes an increase in potential on the anode of the opposite device which in turn, because of the capacity between it and the control electrode of the first device, tends to vary the potential on the control electrode of the first device in the positive direction producing an accumulative action whereby one device becomes 10 saturated and the other device becomes cutoff. After discharge of that one of the two condensers which maintains its respective control electrode negative to a point such that current flows in the corresponding discharge device, the accumulative 15 action again occurs and the device which was first non-conducting becomes conductive and the other becomes non-conducting. In this way, the two devices become conducting cyclically and at a frequency which is dependent upon the position of 20 the tap 22. Thus pulses of current flow in the resistances 9, 10 and in the cathode resistances 13 and 14.

Resistance 14 may be included in the anode-cathode circuit of a third electron discharge device 35 comprising cathode 25, anode 27 and control electrode 28, which device is likewise connected across the source of operating potential through the cathode resistance 14 and anode resistance 29. When a pulse of current flows in 40 resistance 14, the current in the device 25, 27, 29 is reduced and thus a corresponding pulse in the positive direction appears between conductors 30 and 33 to which a suitable load may be connected.

45 If desired, however, positive pulses may also be taken from conductors 30 and 34.

It is frequently desirable that the pulses produced by the multivibrator thus described be synchronized by a source of pulses represented by 50 the circle 40, which source is connected between the control electrode of discharge device 46 and the cathode thereof. The cathode of device 46 is connected to the cathode 5 and the anode is connected through a resistance 47 and resistance 11 to the source of anode operation potential. If

desired, the device 46 may be in the same envelope with the electrodes 3, 4 and 5, as illustrated. In operation pulses produced by source 40 are transmitted by device 46 and appear on resistance 13. These pulses vary the potential on cathode 5 in a positive direction with respect to ground and thus tend to interrupt current between anode 3 and cathode 5. When this happens, the anode potential of device 3 rises thereby driving the control electrode 7 positive, which increases the current in device 2 thereby reducing the potential on the anode 6 which, through action of condenser 16, renders the control electrode 4 more negative with respect to the cathode thereby further reducing the current in device 1. Through this action the multivibrator is synchronized with the pulses from the source 40.

It may happen, however, that undesired capacity exists between the anode 48 of device 46 and the anode 3. This capacity may exist by reason of the fact that these two anodes are enclosed in the same envelope or it may exist by reason of external circuit connections. Such capacity is indicated in dotted lines at 49. It will be seen that, owing to the coupling resistance 13 which couples the device 46 in the device 1, the potential on the anode of these two devices varies oppositely; that is, when current flows in device 46, its anode potential drops. The resulting potential on resistance 13, however, reduces the current in anode 3 causing that anode potential to rise. This is the desired action of the device. However, the drop in potential on anode 48 may be transmitted to the anode 3 through capacity 49 during the initial part of the pulse. This capacity may be sufficiently great that the multivibrator is synchronized by the potential supplied to the anode device 3 through capacity 49 rather than by the potential on resistance 13. The effect, in that case, is that the multivibrator produces a positive pulse when it is desired that it produce a negative pulse.

To avoid this effect and in accordance with my invention, the condenser 50 is included in the circuit between the anode 48 and the anode 6. When the potential of anode 3 varies in the positive direction, the potential of anode 6 varies in the negative direction. The potential variation on the anode 48 is supplied to both of the anodes 3 and 6, one of which varies in a positive direction and the other in a negative direction. Thus the effect of capacitance 49 is neutralized by the capacitance 50. In other words, when the potential of anode 48 drops due to current flowing therein, it tends to cause the potential on anode 3 to drop by action of capacitance 49. However, at the same time, the potential on anode 6 rises which in turn, through capacitances 50 and 49, tends to increase the potential on anode 3, this tendency just neutralizing the tend-

ency produced by the rise in potential on anode 48 due to capacitance 49 alone.

While I have shown a particular embodiment of my invention, it will, of course, be understood that I do not wish to be limited thereto since different modifications may be made both in the circuit arrangement and in the instrumentalities employed, and I contemplate by the appended claims to cover any such modifications as fall within the true spirit and scope of my invention.

What I claim as new and desire to secure by Letters Patent of the United States, is:

5 1. In combination, a multivibrator comprising a pair of electron discharge devices connected in multivibrator relationship, a third electron discharge device, means to supply pulses of current through said third device to one of said pairs of devices to interrupt current therein, whereby the potentials on the anodes of said third and said 10 one device vary oppositely, and undesired capacity coupling between the anodes of said third and said one device tends to oppose said opposite variations, and means responsive to current in the second of said pair of devices to neutralize the effect of said undesired capacity.

20 2. In combination, a multivibrator comprising a pair of electron discharge devices connected in multivibrator relationship, a third electron discharge device having an anode having capacitive coupling to the anode of one of said pair of devices, means responsive to current in said third device to reduce current in said one device thereby to synchronize said multivibrator with current variations in said third device, and capacity 25 coupling between the anode of said third device and the anode of the second of said pair of devices proportioned to neutralize the effect of said first capacity coupling on the anode of said one device.

30 3. In combination, a multivibrator comprising a pair of electron discharge devices connected in multivibrator relationship, and each having an anode and a cathode, a third electron discharge device having a cathode and anode, a source of 35 operating potential having a positive terminal connected through individual resistances to all of said anodes and having a negative terminal connected to all of said cathodes, a common resistance in circuit between said negative terminal and the cathodes of said third device and one of said pair of devices and individual capacity coupling between the anode of said third device and the respective anodes of said pair of devices said coupling being proportioned to reduce the effect on the anode of said one device of capacity between said anode and the anode of said third device, and a pulse source connected to said third device to synchronize said multivibrator.

60 EVERHARD H. B. BARTELINK.
